Primary Examiner — Karen E Eldridge Powers*Assistant Examiner* — Margaret Leah Bryan*(74) Attorney, Agent, or Firm* — Faegre Drinker Biddle & Reath LLP(57) **CLAIM**

The ornamental design for accessory for a hairdryer, as shown and described.

DESCRIPTION

FIG. 1 is a front, top and right-side perspective view of an accessory for a hairdryer, illustrating our new design; FIG. 2 is a front elevational view thereof; FIG. 3 is a top plan view thereof; FIG. 4 is a left-side view thereof; FIG. 5 is a right-side view thereof; FIG. 6 is a rear elevational view thereof; and, FIG. 7 is a bottom plan view thereof.

(Continued)

The broken lines illustrate portions of the accessory for a hairdryer that form no part of the claimed design. The dash-dot broken line illustrates a boundary of the claimed design and forms no part of the claimed design.

1 Claim, 7 Drawing Sheets
